ASH RECEPTACLE

John Visser, Grand Rapids, Mich., assignor, by
mesne assignments, to F. L. Jacobs Co., De-
troit, Mich., a corporation of Michigan

Application March 17, 1937, Serial No. 131,294

6 Claims. (Cl. 206—19.5)

This invention relates to ash receptacles, and more particularly to improvements in tilting ash receptacles and ash receptacle assemblies of the flush type commonly used in motor vehicles, busses, airplanes, booths for serving refreshments, and other similar places.

It is an object of this invention to provide a novel ash receptacle and ash receptacle assembly which is economical to manufacture and which is rugged and reliable in use.

Another object of this invention is to provide a novel ash receptacle and ash receptacle assembly having a novel bearing support for pivotally mounting the ash receptacle.

A further object of this invention is to provide a novel means for supporting an ash receptacle of the tilting type, said means acting both as a pivot for the ash receptacle and as a stiffening member for the support or panel upon which the ash receptacle is mounted.

Another and further object of this invention is to form the stationary portion of the pivotal means of an ash receptacle assembly from a stiffening rib adjacent the opening cut in the supporting means for the ash receiver.

Another and still further object of this invention is to provide a pivotal means for the ash receiver which may also serve as a stiffening means for the entire instrument panel into which the ash receiver, together with the other instrument commonly employed thereon may be mounted.

The novel features which I believe to be characteristic of my invention are set forth with particularity in the appended claims. My invention itself, however, both as to its organization and manner of construction, together with further objects and advantages thereof, may best be understood by reference to the following description, taken in connection with the accompanying drawing, in which:

Figure 1 is a front elevational view of an ash receptacle in closed position in its cooperating mounting panel, the outline of the ash receiver box and the opening in the support being shown by the dotted lines;

Figure 2 is a side elevational view partly in cross section of the ash receptacle as shown in Figure 1;

Figure 3 is a side elevational view partly in cross section of the ash receptacle assembly showing the ash receiving box in its open position, but illustrating a slightly different form of bearing support for the ash receptacle than that shown in Figure 2;

Figure 4 is a fragmentary isometric view of the ash receptacle support illustrated in Figure 3; and

Figure 5 is a fragmentary isometric view similar to Figure 4 illustrating in detail the support shown in Figure 2 which comprises a rib member which is secured to a radially extending portion of the main support and to the inturned lower edge of the opening in the support.

The ash receptacle assembly illustrated in the 10 various figures of the drawing comprises in general a supporting member 1 having an opening 2 within which an ash receptacle 3 is pivotally mounted for limited angular movement there-through. Support 1 may, of course, be a portion 15 of the main panel member in which the ash receptacle is to be mounted, or it may comprise an auxiliary panel member which is adapted to be secured to the main panel in which the ash receptacle is to be mounted. As may be seen best 20 in Figures 2 and 3 of the drawing a cover portion or member 4 is provided for the ash receptacle when it is in its closed position may be formed by bending rearwardly a portion of the stock cut free from the support member 1 to form the 25 opening 2. For a reason which will presently appear the cover member 4 is provided with two downwardly extending spaced bearing ribs 5.

In order to provide a suitable bearing member 30 for pivotally supporting the ash receptacle 3, a portion of the stock cut loose in forming the opening 2 in the support 1 is laterally bent backward adjacent the lower edge of the opening 2 as shown at 6. As is shown in Figures 2 to 5 inclusive of the drawing the lower portion of the 35 support or panel member 1 is bent rearwardly as at 7, and the outer extremity 8 is bent upwardly to increase the stiffness or rigidity of this portion of the support or panel member 1.

In the preferred embodiment of the invention 40 as illustrated in Figures 2 and 5 of the drawing the bearing surface upon which the tilting ash receptacle is supported is provided by an auxiliary member 9 which is secured to the rearwardly extending portion 7 of support 1 in any 45 suitable manner such as by spot welding or the like. Auxiliary member 9 includes a tail portion 10 which lies in intimate contact with the rearwardly extending portion 7, a curved portion 11 which acts as the bearing surface for the ash 50 receptacle 3, and an undeturned lip portion 12 which is secured to cut-out portion 6 of box 1 in some suitable manner such as by spot welding.

Due to the manner in which auxiliary member 9 cooperates with the support 1, it will be at once 55

apparent that this auxiliary member 9 acts not only as a bearing support for the ash receptacle 3 but also acts as a stiffening member for the entire ash receptacle assembly. Inasmuch as the 5 cut-out portion 6 is bent inwardly from the normal surface of the support or panel member 1, it is obvious that auxiliary member 9 may extend laterally beyond the side edges of the opening 2 and even across the entire width of the 10 support or panel member 1.

The ash receptacle or ash receiving box 3 comprises two side walls 13, a front wall 14, a rear wall 15, and a bottom wall 16. The walls 14, 15, and 16 are preferably blanked from a single 15 piece of material and then bent into U shape and fastened to the side walls 13. The side walls are provided with flanges turned to engage the walls 14, 15, and 16. These parts are then secured together in some suitable manner such as by spot welding. An ornamental front panel 18 is secured to the front wall of the box. An operating handle or knob 17 is mounted centrally on the front face of the ornamental panel 18.

25 The top edges of the side walls 13 are curved to lie under the curved cover portion 4 of support 1. In order to minimize wear due to friction between the relative moving parts of the ash receptacle assembly, each side wall 13 is provided along its upper curved edge with a spacing rib 19. This provision of a spacing rib or ribs on one of the elements of the ash receptacle assembly is described in detail and claimed in 30 my copending application Serial No. 131,293, filed 35 March 17, 1937, and assigned to the same assignee as the present invention.

In order to provide a suitable rocker arm for engaging the bearing surface 11 of auxiliary member 9, the bottom edge of each side wall 13 40 is extended below the bottom wall 16 to form rocker arms 20 which have a bearing surface 21' which is complementary to the bearing surface 11 of auxiliary member 9. The bearing surface 21' of rocker arm 20 is thus adapted 45 to be seated upon the bearing surface 11 and thus permits limited angular pivotal movement of the ash receptacle 3 within the opening 2.

To provide suitable spring biasing means for 50 the ash receptacle 3, a spring member 21 having a configuration similar to that as shown in Figure 2 of the drawing is secured to the rear wall 15 of the ash receptacle 3 in some suitable manner such as by spaced locking ears 22'. From the 55 point at which the spring member 21 is secured to the rear wall 15, it extends first rearwardly as at 22, then upwardly and forwardly as at 23, and finally forwardly in a free end portion as at 24. Between the portions 23 and 24 of spring member 21 a hump portion 25 is provided for 60 engaging the cover portion 4 of support 1. Inasmuch as the hump portion 25 of spring member 21 is arranged to ride along the downwardly extending spaced bearing rib 5 of the cover portion 4 of support 1, it is apparent that wear due to friction between the spring member 21 and the cover portion 4 is reduced to a minimum.

To limit the outward movement of ash receptacle 3, a downwardly and slightly rearwardly 70 extending tongue 26 is punched out of support 1. A cooperating laterally extending slot (not shown) is provided on the front face of hump portion 25. It will thus be apparent that as the ash receptacle 3 is rocked or rotated to its 75 open position, the outward movement of the

ash receptacle 3 is limited by reason of the fact that the downwardly extending tongue 26 engages the slot in hump portion 25 of spring member 21. In order to completely remove ash receptacle 3 from support or panel member 1, it is merely necessary to depress free end portion 24 of spring member 21 to an extent sufficient to disengage the slot in hump portion 25 from tongue 26. The ash receptacle 3 may then be readily removed from support 1. In reassembling 10 the ash receptacle 3 in the support 1, the rocker arms 20 are disposed over the bearing surface 11 of the support, and the ash receptacle 3 may then be readily rocked to its closed position, spring member 21 being cammed under the downwardly extending tongue 26.

To provide a more positive biasing of the ash receptacle 3 in its closed position, the cover portion 4 of support 1 is deflected upwardly as at 27. It thus requires a slightly greater force 20 to initiate outward movement of the ash receptacle 3 than it does to continue the outward movement as the spring member 21 rides along the spaced bearing ribs 5 of the cover portion 4. Similarly, as the ash receptacle 3 is moved to its closed position, a spring-closing, snap-shut action is obtained as the ash receptacle 3 approaches its final closed position.

In order that the spring 21 may flex freely about the point at which it is secured to the ash receiving box, and to prevent a shift in the fulcrum point of the spring 21, the rear wall 15 preferably does not extend up as high as the top rear edges of the side walls 13 (see Figure 2).

In Figures 3 and 4 of the drawing, a slightly different embodiment of this invention is illustrated. In order to further minimize the costs of production of the ash receptacle assembly, it has been found desirable under certain circumstances to eliminate the auxiliary member 9 which is shown in the preferred embodiment of the invention. Under these circumstances, the rearwardly extending portion 40 of the stock which has been cut loose from the main support 1 to form the opening 2 is continued rearwardly to be shaped in the manner shown in Figures 3 and 4 to form a bearing surface 28 which is complementary to the bearing surface 21' of the rocker arms 20 of the ash receptacle 3. Although this construction does not provide as great a stiffening effect as was described in connection with the preferred embodiment of the invention, it is obvious that the ash receptacle assembly is stiffened to a very appreciable extent by this form. The remainder of the ash receptacle assembly illustrated in Figures 3 and 4 of the drawing is similar to that illustrated in Figures 1, 2 and 5, and similar parts have been given similar reference characters.

In order to further enhance the general appearance of the ash receptacle assembly, the lower edge 29 of the ornamental front panel 18 of the ash receptacle 3 is curved gradually rearwardly. Due to the particular nature of the mounting means for the ash receptacle 3, the lower edge 29 of the ornamental panel 18 can move smoothly in spaced relationship to the curved front corner 30 of the support 1. (See Figures 2 and 3.) As will be at once apparent to those skilled in the art, this provides a very pleasing and ornamental effect for the ash receptacle assembly. The ornamental appearance of the front panel 18 may be further improved 75

by providing the face thereof with ornamental ribs 31.

While I have shown a particular embodiment of my invention, it will, of course, be understood that I do not wish to be limited thereto, since many modifications may be made, and I, therefore, contemplate by the appended claims to cover all such modifications as fall within the true spirit and scope of my invention.

10 I claim as my invention:

1. In an ash receptacle assembly, the combination comprising a supporting panel of sheet material having an opening therein defined by an upper tab and a lower tab, said tabs being pressed from said panel and extending rearwardly therefrom, and an ash receiving box mounted for angular movement through said opening, said upper tab being disposed to substantially cover said box when said box is in closed position in said supporting panel, said box being in fitting engagement with said tabs, and said lower tab being disposed to form a rocking bearing surface about which said box may be rocked.

2. In an ash receptacle assembly, the combination comprising a supporting panel of sheet material having an opening therein defined by an upper tab and a lower tab punched from said panel, an ash receiving box mounted for angular movement through said opening, said upper tab extending rearwardly over the top of said box to substantially cover said box when said box is in closed position in said supporting panel, and a bearing member secured to said panel having a curved bearing surface one edge of which overlaps said lower tab, said box having a complementary bearing surface for engaging said first bearing surface, thereby to permit angular movement of said box thereabout.

3. In an ash receptacle assembly, the combination comprising a supporting panel having an opening therein, an auxiliary member having a curved bearing surface of relatively large radius of curvature secured to said supporting panel, an ash receptacle disposed for rotational movement through said opening having a bearing surface thereon complementary to said first bearing surface, and spring biasing means for maintaining said bearing surface of said ash receptacle in contact with said bearing surface of said auxiliary member, said auxiliary member extending laterally a substantial distance beyond either side of said opening.

4. In combination, a withdrawable and insertable ash receptacle comprising a body including a main body portion and a movable wall portion,

said body having an opening near its top and a longitudinal median plane, said plane being curved in the shape of an arc of a circle, said movable wall portion being movably mounted at the inner end of said main body portion, and a guiding framework for slidably receiving said body and in which said body is retractably inserted, the top end of said movable wall portion being concealed by said framework when said body is inserted therein, said framework including a 10 curved bearing surface at the top of said body and a lower bearing surface convexly curved in the direction of the movement of said body as it is bodily inserted in and retracted from said framework, said receptacle having a sliding and fitting engagement with said curved bearing surfaces.

5. In an ash receptacle structure, a metal panel having an opening formed by portions depressed rearwardly therefrom including integral upwardly and downwardly turned portions disposed at the top and bottom respectively of the opening, and an ash receptacle tiltably disposed in said opening, said upwardly turned portion being formed into a rearwardly extending arcuate cover for closing the top of said receptacle, and said downwardly turned portion being formed into a curved bearing for the receptacle, said receptacle having its top and bottom sides shaped complementary to said cover and curved bearing respectively and in fitting engagement therewith whereby said receptacle may be swung over an arcuate path defined by said two turned portions into and out of said panel opening.

6. In an ash receptacle structure, a metal panel having an opening formed by portions depressed rearwardly therefrom including integral upwardly and downwardly turned portions disposed at the top and bottom respectively of the opening, an ash receptacle tiltably disposed in said opening, said upwardly turned portion being formed into a rearwardly extending arcuate cover for closing the top of said receptacle, and said downwardly turned portion being formed into a curved bearing for the receptacle, said receptacle having its top and bottom sides shaped complementary to said cover and curved bearing respectively and in fitting engagement therewith whereby said receptacle may be swung over an arcuate path defined by said two turned portions into and out of said panel opening, and means for maintaining anti-rattle cooperation of said receptacle with said turned portions.

JOHN VISSER. 55
